OR

D 13,270

UNITED STATES PATENT OFFICE.

FRAZER CHRISTIE, OF PHILADELPHIA, PENNSYLVANIA, ASSIGNOR TO WILLIAM STEWART'S SONS, OF SAME PLACE.

DESIGN FOR A TURCOMAN.

SPECIFICATION forming part of Design No. 13,270, dated August 29, 1882.

Application filed July 21, 1882. Term of patent 3½ years.

To all whom it may concern:

Be it known that I, FRAZER CHRISTIE, of Philadelphia, county of Philadelphia, and State of Pennsylvania, have invented and produced a new and original Design for a Turcoman, of which the following is a specification.

The nature of my design is fully represented in the accompanying photographic illustration, to which reference is made.

I claim as my invention—

The design for a turcoman, as shown.

Witnesses: FRAZER RIS

JAS. McGEOGH,

JOS. FAY.
